UNITED STATES PATENT OFFICE

2,579,105

GAME TEACHING APPARATUS

Joseph James Baldine, Hubbard, Ohio

Application January 26, 1951, Serial No. 207,919

1 Claim. (Cl. 35—29)

1. *Artemesia annua* L. (Malaria-herb) 2. *Artemesia annua* L. (Malaria-herb)

1. Introduction

The present invention relates to improvements in game teaching apparatus, and more particularly to an apparatus which is particularly adapted for teaching plays in a game, such as football.

An object of the present invention is to provide a game teaching apparatus which includes the provision of a gameboard bearing indicia of a particular game field and playing pieces magnetically retained on the gameboard and indicating the players of the game.

A further object of the present invention resides in the novel construction of the gameboard as being comprised of a pair of rectangular, light weight, flat plates hingedly connected and having a magnetic sheeting covering the light-weight plates, whereby magnetic playing elements can be disposed on the gameboard for removable positioning at preselected points.

A still further object of the present invention resides in the novel construction of the game pieces used in combination with the gameboard, the game pieces being comprised of cylindrical members, each having a bore therethrough with a spring retainer disposed in one end of the bore and a chalk means reciprocably disposed in the opposing end of the bore, a spring being disposed between the retainer and chock means for urging the chalk outwardly for marking engagement with the surface of the gameboard.

Another object of the present invention resides in the provision of a directional arrow adapted to be positioned on the upper surface of the cylindrical member to indicate the direction of travel of the game piece in combination with the marked indication of the pass travel of the game piece, as designated by the chalk marking on the game-board.

Another object of the present invention resides in the provision of a retainer in the bore of the cylindrical member which is of magnetic material, thereby to attract the directional arrow and retain the same on the upper surface of the cylindrical member.

A still further object of the present invention resides in the provision of a simple clip secured to the retainer in the bore of the cylindrical member for removably retaining the directional arrow on the upper surface of the game piece.

Still another object of the present invention resides in the provision of the cylindrical member with a plurality of projections on its lower face with a magnetic disk being disposed on that face and retained by the plurality of projections, whereby the playing piece can be removably positioned on the gameboard at preselected positions.

Various other objects and advantages will become apparent from the detailed description to follow. The best form in which I have contemplated applying my invention is clearly illustrated in the accompanying drawings, wherein:

Figure 1 is a top plan view of the gameboard with a plurality of game pieces disposed thereon;

Figure 2 is a vertical longitudinal sectional view taken substantially along the plane of line 5—5 of Figure 1;

Figure 3 is a detail perspective view of the gameboard shown in folded relation;

Figure 4 is a top plan view of one of the game pieces of the present invention showing a directional arrow mounted thereon;

Figure 5 is a vertical sectional view taken substantially along the plane of line 5—5 of Figure 6;

Figure 6 is a bottom plan view of the game piece of Figures 4 and 5;

Figure 7 is a detail perspective view of the chalk means and spring therefor;

Figure 8 is a detail perspective view of the directional arrow employed in combination with the game piece of the present invention; and

Figure 9 is a detail perspective view of a modified form of game piece wherein a spring clip is provided for retaining the directional arrow on the upper face of the cylindrical member of the game piece rather than the magnetic retainer of Figures 4 through 6.

35 Referring more particularly to the drawings, wherein like numerals designate like parts throughout, the numeral 10 designates generally the gameboard with which the game pieces of the present invention are to be employed, the game pieces being designated generally by the numeral 12.

The gameboard 10 is disclosed in Figures 1 through 3 as comprising a pair of rectangular flat members formed of a lightweight material, such as aluminum, the two plates 14 and 16 being hingedly connected together by means of the conventional hinge 18 having the pins, screws or the like 20 extending therethrough. Each of the plates 14 and 16 is covered with a metallic sheeting 22, steel, preferably, being used for magnetic purposes. The sheeting 22 is angulated at its peripheral portions for engagement over the peripheral portions of the plates 14 and 16, as shown at 24 and 26.

55 The metallic sheeting 22 may be provided with indicia markings 28 for designating the type of field desired, the one shown being a football field. Of course, suitably constructed goal posts 30 may

be provided for positioning at opposite ends of the gameboard.

Looking now at Figures 4 through 7, the game piece will be seen to comprise a cylindrical member 32 having a bore 34 axially extending therethrough with a lower reduced diameter portion at 36. The upper end of the bore 34 is threaded, at 38, for receiving the spring retainer 40 with the spring retainer 40 being formed of magnetic material.

The lower end of the cylindrical member 32 is provided with a plurality of projections 42 and a metallic disk of magnetic material 44 is engaged with the bottom face of the cylindrical member 32 and has a plurality of openings formed therein for receiving the projections 42. The projections 42 are then peened to retain the disk 44 on the cylindrical member 32. The disk 44 is also provided with a central aperture 46 for a purpose to be hereinafter described.

Disposed within the bore of the cylindrical member 32 is a chalk means 11 which is comprised of a cup-like element 48 having a flange 50, a conventional piece of chalk 52 having one end received in the cup-like element 48. The flange 50 is adapted to abut against the shoulder 54 formed between the bore 34 and the reduced diameter portion 36. The chalk piece 52 extends outwardly through the reduced diameter bore 36 and the opening 46 in the disk 44.

A compression spring of coil form 56 is disposed within the bore 34 and engages the spring retainer 40 at one end and the flange 50 at the other end, intermediate portions of the spring encircling the cup-like element 48.

The directional arrow 13, shown best in Figure 8, is comprised of an arrowhead 58 and a wire 60 integrally secured thereto. The wire 60 is of angulated form consisting of a plurality of V-shaped sections 62. The wire 60 is of readily bendable material whereby the direction of travel can be indicated as following an arc, or, if desired, as a sharp shift in direction.

The directional arrow 13 is adapted to be disposed on the upper face of the cylindrical member 32, with an intermediate portion of the wire 60 being disposed over the retainer 40 for magnetic retention thereby.

In the modified form shown in Figure 9, the retaining element 40 is provided with a spring clip 64 which is adapted to receive an intermedi-

ate portion of the wire 60 for retaining the arrow 13 on the cylindrical member 32.

In the form of the invention shown in Figures 4 through 6, the retainer 40 can be removed by inserting a tool in the holes 41, whereas in the form shown in Figure 9 the retainer 40 can be removed by rotating the spring clip 64.

In view of the foregoing, it is believed that a device has been provided which will accomplish all of the objects hereinabove set forth.

Having thus described the invention, what is claimed as new is:

A game piece comprising a cylindrical body having upper and lower ends and provided with an axial bore including a screw-threaded upper portion and an annular shoulder adjacent the lower end thereof, a screw threaded plug in the threaded portion of said bore, a resilient clamp provided on the top of said plug, a pointer positioned diametrically on the upper end of said body and having an intermediate portion thereof frictionally engaged by said clamp, a compression spring positioned in said bore and abutting said plug with its upper end, an inverted cup provided in the lower portion of said spring and having an outturned marginal flange at its lower edge engageable with said shoulder, a disc-shaped magnet provided at the lower end of said body, keeper pins projecting from the lower end of the body and secured in apertures formed in said magnet, said magnet having a central opening in register with said bore, and a chalk mounted in said cup and projecting downwardly through the opening in said magnet.

JOSEPH JAMES BALDINE.
